LOCOMOTIVE BOILER

Filed March 20, 1926

Inventor
Charles G. Hawley
Bentonville, Wilson, Mo.

UNITED STATES PATENT OFFICE.

CHARLES GILBERT HAWLEY, OF CLEVELAND, OHIO, ASSIGNOR TO LOCOMOTIVE FIRE-BOX COMPANY, OF CHICAGO, ILLINOIS, A CORPORATION OF DELAWARE.

LOCOMOTIVE BOILER.

Application filed March 20, 1926. Serial No. 96,135.

This invention relates to improvements in locomotive boilers and it consists of the matters hereinafter described and more particularly pointed out in the appended claims.

The primary object of the present invention is to provide a simple and efficient means directly associated with the flue sheet of the boiler, which operates in that part of the fall in boiler water level, initially uncovering or exposing a part of the crown sheet adjacent the flue sheet, to limit the same to an area which is safe in practice but will act to permit a leakage of a small amount of steam into the firebox, sufficient to be observed in the stoking of the firebox, thereby informing the fireman of the actual water level in the boiler, irrespective of the level indicated by the usual gages.

A further object of the invention is to provide in the flue sheet, between predetermined vertical rows of flues therein, channels which are open at the top and bottom only and which act to deliver water upon the head of the crown sheet near the flue sheet end, in such amounts as to limit the dry spot on the crown sheet uncovered by a falling water level to one of small dimensions, and about the stay bolts of which, steam escapes into the firebox to be observed by the one stoking the firebox.

These objects of the invention as well as others, together with the many advantages thereof will more fully appear as I proceed with my specification.

In the drawings:—

Fig. 1 is a vertical longitudinal sectional view through the firebox end of a locomotive boiler embodying my invention.

Fig. 2 is a vertical transverse section through the same as taken on the line 2—2 of Fig. 1.

Fig. 3 is a detail horizontal sectional view on an enlarged scale as taken on the line 3—3 of Fig. 1.

Fig. 4 is an enlarged detail view of parts shown in Fig. 1 and which will be more fully referred to later.

Referring now in detail to that embodiment of the invention illustrated in the accompanying drawings:—1 indicates the back or door sheet of the firebox and 2 indicates the flue sheet thereof and forming a continuation of the flue sheet, is the inside throat sheet 3. The sides of the firebox are formed

by the transversely arched or curved crown sheet 5 which merges into the firebox side sheets 4—4. Said side sheets and crown sheet extend between and are connected at their ends to the back sheet 1 and flue and throat sheets 2 and 3 respectively, the crown sheet being inclined upwardly from the back sheet toward the flue sheet so that its highest point or head 6 is at the flue sheet end thereof.

The wrapper of the boiler includes a roof sheet 7, a back head 8, outer firebox sheets 9—9 and an outer throat sheet 10 together with a boiler shell 11, all in the manner well known. The front and rear water legs 12 and 13 and the side water legs 14—14 are all closed at the bottom by a mud ring 15, while the bottom of the firebox is formed by the grate indicated by the dotted line 16 in Fig. 1. In the back head and back sheet respectively is formed the fuel door opening 17 and extending forwardly from the flue sheet 2 are the flues or tubes 18 through which the products of combustion from the firebox are drawn to the smoke box at the front end of the boiler (not shown) in the manner well known. The roof sheet and crown sheet are connected by the usual stay bolts 19, as are the side sheets 4 and 9, throat sheets 3 and 10 and back sheets 1 and 8 respectively. The construction just described is typical of that type of locomotive boiler now in general use and need not be described in greater detail.

In locomotive practice, the usual water level desired to be maintained, is such as to keep the crown sheet submerged at all times. However due to the amount of water generated into steam for the intended purpose of the locomotive, the water level falls. Gage glasses in the cab are intended to indicate the levels of the water but such devices are often inaccurate, not always due to any faulty construction therein, but to certain boiler conditions such as surges and foamings which will produce in the gage glasses, levels which do not correspond to the actual water level in the boiler. When the real water level falls below that point, good locomotive practice demands be maintained, the first part of the crown sheet to be uncovered thereby, is that point of highest elevation and which point is usually the head 6 of the crown sheet, which is located in the longitudinal median plane of the transversely curved crown sheet. Such a level as will uncover or

expose this part of the crown sheet is best indicated at 20 in Figs. 1 and 4.

To maintain or limit the uncovered or dry area on the crown sheet head or high end, to 5 one of as small a dimension as possible, I provide means directly associated with the flue sheet for conducting water from the bottom of the boiler space to the top of and to the rear of said flue sheet, which water is flooded or 10 washed over the lateral portions of said crown sheet to limit the dry area as best shown at 21 in Fig. 3. In the flue sheet, I form spaced vertical portions thereof, between adjacent 15 rows of flues, to provide rearwardly extending channels 22—22 which preferably taper in cross sectional area from the top to the bottom end, said channels opening into the boiler water space to the front of said flue sheet. On said flue sheet 2 in the plane of each channel 20 I secure an upright plate or strip 23 which terminates at its top end flush with the crown sheet, and terminates at its bottom end above the bottom of said channel to provide an inlet 24 as best shown in Fig. 1. Water from the 25 bottom boiler water space, enters the inlets 24 and rises in said channel to be discharged out through the top ends thereof. The water issuing from the top end of the conduits floods in all directions, and that water flooding or 30 washing toward the median line of the crown sheet will limit the area of the dry spot thereon to one of small dimensions. Even though an excess of water be flooded upon the crown sheet head, which would completely cover or 35 wash over the area of said head, there would be nothing detrimental in such action because as long as the crown sheet is submerged or covered with water, no dangerous conditions can arise. However it is not the intended 40 purpose of said conduits to completely flood or wash the head of the crown sheet.

As soon as that water level approaches which will uncover said area of the head, that portion of the crown sheet becomes dry and 45 excessively hot and somewhat softens so that the steam pressure in the boiler causes it to buckle or bend downwardly into the firebox. As the flexing commences, said portion of the crown sheet tends to pull away from the stay 50 bolts 19 therein so that steam escapes in a continuous jet in the firebox as best shown in Fig. 4. When such a condition is observed by the fireman during the stoking of the firebox, more water is fed to the boiler to reestablish 55 the desired safe water level which completely submerges all portions of the crown sheet. Thereafter there may be a leakage of a small amount of water into the firebox but such a leakage will be immaterial because the locomotive is withdrawn from service at the first 60 opportunity along the run. As the fuel door

is opened at frequent intervals and in many cases is left open, the presence of steam blowing into the firebox is instantly observed and as instantly warns the engine crew that something is wrong in the boiler water level even though the gage glasses indicate a sufficient amount of water in the boiler so that the water level conditions may be rectified. Thus the construction just described constitutes a positive low water telltale or indicator which operates from that portion of the boiler directly affected and cannot prove false in its telling or indication. 65 70

While in describing my invention, I have referred to certain details of mechanical construction as well as form and arrangement of the parts thereof, I do not wish to be limited thereto except as may be pointed out in the appended claims. 75 80

I claim as my invention:—

1. A locomotive boiler embodying therein, a firebox including a crown sheet and a flue sheet, the crown sheet having an elevated portion, and means directly associated with the flue sheet and forming channels operating at a predetermined low water level for flowing water upon that portion of the crown sheet which would otherwise be exposed at said low level, said channels opening at one end 85 through the crown sheet and at their other end through the flue sheet and being adapted to isolate and maintain a portion of limited size of said crown sheet so as to act as a low water telltale. 90 95

2. A locomotive boiler embodying therein, a firebox including a crown sheet having a raised head at one end and a flue sheet, said flue sheet being formed to provide vertically disposed channels therein, plates closing the open fronts of said channels thus providing conduits opening at their bottom ends into the lower boiler water space and opening at their 100 top ends through the crown sheet at opposite sides of the head so as to supply boiler water to said sides of the head and thereby limit the size of the exposed area of the head upon the fall of the boiler water level below that of the crown sheet head. 105

3. A locomotive boiler embodying therein, a firebox including a crown sheet and a flue sheet, said flue sheet being formed to provide a plurality of channels of tapering cross sectional diameter from top to bottom, a plate fixed to the flue sheet and extending across each channel and terminating short of the bottom end thereof, each channel opening through the crown sheet at the flue sheet end thereof. 110 115

In testimony whereof, I have hereunto set my hand this 16 day of March, 1926.

CHARLES GILBERT HAWLEY.
